RIVET FEEDING DEVICE

William R. Kovacs, Cleveland, Ohio, assignor
to The Cleveland Pneumatic Tool Company,
Cleveland, Ohio, a corporation of Ohio

Application September 25, 1943, Serial No. 503,764

3 Claims. (Cl. 78—46)

1

The present invention relates to improvements in devices for manually inserting rivets or the like into work openings and aims to provide a device of this kind which is more satisfactory and efficient than previous devices and is less likely to become jammed or to cause marring of the work.

The primary object of the invention resides in the provision of a rivet feeding device embodying improved means for releasably holding a plurality of rivets in position to be individually discharged from the delivery end of the device.

A further object of the invention is to provide an improved device of the above character in which there are employed resilient fingers for retaining the rivets in the tube which are adapted to be engaged and spread by the delivery end of the tube for releasing the rivets therefrom, and means engaging said fingers for retaining the innermost rivet in position to preclude its premature discharge from the tube until said device is in the desired position for releasing said rivet.

A still further object of the invention is to provide an improved device of the character mentioned in which the tube and a resilient thrust member or nose piece engageable with the work are relatively movable for causing spreading of the resilient fingers and in which the thrust member is of a form such that it is not likely to cause marring of the work.

Other objects and advantages more or less ancillary to the foregoing reside in the specific construction and arrangement of the elements peculiar to this structure, as will become apparent from a more complete examination of this specification.

In the drawing which illustrates the invention:

Fig. 1 is a perspective view illustrating a rivet placing device embodying the features of the present invention, the cover of the device being illustrated in open position in full lines and in closed position in broken lines.

Fig. 2 is an end view thereof.

Fig. 3 is a fragmentary vertical sectional view taken substantially on line 3—3 of Fig. 2.

Fig. 4 is a sectional view similar to Fig. 3 with the parts in a different position.

Fig. 5 is a perspective view showing the relation between rivet gripping fingers and the feet which engage the work when the device is pushed forward for inserting a rivet into a rivet hole.

Referring to the drawing for a more detailed description thereof, the improved rivet feeding or placing device is generally designated by the reference numeral 8 and includes an elongated

2

hollow member or tube 9 which forms a support or magazine adapted to contain a plurality of rivets 10 or other articles to be fed. The tube 9 is open at both ends thereof and is fabricated 5 with a longitudinal slot 11 in the wall thereof. A plunger 12 is adapted to be inserted through the open outer end 13 of the tube for engagement with the outer end of the series of rivets previously placed in the tube as shown in Figs. 3 10 and 4, said plunger being formed with a lug 14 which projects through the slot 11 and is movable therealong. A tension spring 15 is connected to the lug 14 and constantly applies a pulling force to the plunger 12, causing the latter to advance the rivets 10 along the tube 9 toward the inner or delivery end 16 thereof.

Soldered or otherwise fixedly mounted on the inner or delivery end 16 of the tube 11 is a bracket 17, said bracket including a sleeve portion 18 surrounding or partially surrounding the tube and a pair of spaced ears 19 and 20 projecting substantially radially of the tube. The ears 19 and 20 form a support for an elongated substantially U-shaped cover 21 which is adapted to be releasably held in closed position adjacent the tube 9 by a spring clip 22 which is carried by the cover and engageable with the tube adjacent its outer end, as shown in broken lines in Fig. 1. The cover 21 is pivotally connected to the ears 19 and 20 30 by means of a transverse pin 23 which permits the cover to be swung toward or away from the tube 9 during the loading of the tube with rivets or the like. Between the ears 19 and 20 there is provided a grooved roller 24 which is rotatably mounted on the pin 23 and around which extends the tension spring 15, said tension spring extending longitudinally within the cover 21 and having its outer end suitably anchored thereto by means of a depressed lug or the like 25.

Mounted on the delivery end 16 of the tube 9 and forwardly of the bracket 17, there is a sleeve 26 formed with a plurality of resilient fingers 27 which normally converge toward the axis of the tube and which are adapted to retain the innermost rivet 28 being fed from said tube. The fingers 27 are stamped from the sleeve 26 and while being of a resilient nature are normally sufficiently rigid to prevent the escape of the innermost rivet 28 as it is urged toward the delivery end of the tube by the spring-urged plunger 12. As a safety feature, however, the present invention aims to provide a means surrounding and in contact with the ends of the resilient fingers 55 whereby said ends are prevented from being

opened to release the innermost rivet until the tube has been moved to rivet feeding position. This safety feature includes a pair of arms 29 which are formed integral with the sleeve 26 and extend toward the delivery end of the tube but diverge outwardly away from the axis of the tube as shown in Figs. 3 and 4. The free ends of the arms 29 carry a member in the form of a yoke 30 formed with an annular portion 31 which overlies and is in contacting engagement with the converging fingers 27. The ends of the arms 29 are fixedly secured in notches formed in the laterally extending ends 32 of the yoke 30. It will thus be seen that the yoke 30, together with the bracket 17, is movable with the tube 9 relative to the sleeve 26 and fingers 27. In the position shown in Fig. 3 of the drawing, the yoke 30 is in frictional engagement with the converging ends of the fingers 27 so that said fingers are prevented from moving outwardly and thereby assures retention of the innermost rivet 28 regardless of the amount of pressure being exerted on the series of rivets by the plunger 12.

A pair of arms 33 extend from the sleeve 26 in parallel relation to the fingers 27. However, the arms 33 extend beyond the fingers and have formed thereon laterally extending lugs 34 providing a bearing surface for engagement with the work 35 and serve to hold the free ends of the resilient fingers 27 in spaced relation to the work so that they can be readily spread apart by the delivery end of the tube without scraping on the work surface. The arms 33 are guided through slots formed in the yoke 30 within the laterally extending ends 32 as more clearly shown in Fig. 2 of the drawing.

It will be seen from the foregoing description that when the tube 9 has been charged with a series of rivets 10, and they are subject to feeding pressure by the plunger 12, the head of the innermost rivet 28 will be engaged by the convergent ends of the resilient fingers 27, and that rivet will be held with the stem thereof projecting from the tip of the device, as shown in Figs. 1 and 2, ready to be inserted into the opening 36 of the work 35. When it is desired to insert the stem of the rivet 28 into the opening 36, the lugs 34 will be brought into engagement with the surface of the work. The arms 33, being integral with the sleeve 26 and the fingers 27, will hold the fingers against longitudinal movement while the tube 9 is being advanced toward the work. As the tube 9 slides forward within the sleeve 26 the arms 29, which are attached to the tube, move forward likewise carrying with them the yoke 30. The restriction to finger movement normally effected by the yoke 30 is thus removed and the delivery end of the tube 9 is brought into engagement with the fingers to spread them apart sufficiently to permit passage of the head of the rivet as shown in Fig. 4. When the rivet head moves past the resilient fingers, the rivet is projected or snapped into the work opening by the action of the spring 15. Thereupon, the tube 9 is released, and under the contracting action of the resilient fingers against the delivery end 16, the tube moves rearwardly in the sleeve 26, and the resilient fingers engage the head of the next rivet and hold the same in readiness for insertion into another opening of the work. Movement of the tube rearwardly carries with it the yoke 30 to again bring said yoke into bearing engagement with the converging ends of the resilient fingers. This action is repeated until the supply of rivets from within

the tube has been exhausted, and when it is desired to obtain an additional supply, the cover 21 is raised to the full line position shown in Fig. 1 which permits the plunger 12 to be removed through the open end 13 by stretching the spring 17 as shown in broken lines in Fig. 1. After loading the tube with rivets from a hopper or other source of supply, the plunger is again positioned in abutting relation with the head of the rivet as shown in the drawing.

Although the foregoing description is necessarily of a detailed character, in order to completely set forth the invention, it is to be understood that the specific terminology is not intended to be restrictive or confining and it is to be further understood that various rearrangements of parts and modifications of structural detail may be resorted to without departing from the scope or spirit of the invention as herein claimed.

20 I claim:

1. In a device for holding and delivering rivets or the like, an elongated hollow member forming a support for a plurality of rivets and having a delivery end, means for urging the rivets toward said delivery end, a sleeve surrounding said hollow member adjacent said delivery end and having convergent resilient fingers adapted to releasably retain the rivets in said hollow member, said hollow member being movable relative to said sleeve for causing said delivery end to engage and spread said fingers for releasing a rivet therefrom, a bracket secured to and carried by said hollow member, a pair of arms extending from said bracket toward the delivery end of said hollow member, and means carried by the free ends of said arms having engagement with the convergent ends of said resilient fingers when the device is withdrawn from the work for preventing expansion of said fingers.

40 2. In a device for holding and delivering rivets or the like, an elongated hollow member forming a support for a plurality of rivets and having a delivery end, means for urging the rivets toward said delivery end, a sleeve surrounding said hollow member adjacent said delivery end and having convergent resilient fingers adapted to releasably retain the rivets in said hollow member, said hollow member being movable relative to said sleeve for causing said delivery end to engage and spread said fingers for releasing a rivet therefrom, a bracket secured to and carried by said hollow member, a pair of arms extending from said bracket toward the delivery end of said hollow member, and a yoke member attached to the free ends of said arms, said yoke member having an annular portion surrounding and engaging the convergent ends of said resilient fingers when the device is withdrawn from the work for preventing expansion of said fingers.

60 3. In a device for holding and delivering rivets and the like, an elongated hollow member forming a support for a plurality of rivets, means for urging the rivets toward the delivery end of said hollow member, a sleeve loosely surrounding said hollow member adjacent its delivery end, having means for engaging the work to space the sleeve a definite distance from the work and having convergent resilient fingers adapted to releasably retain the endmost rivet in the hollow member, the delivery end of said hollow member when the device is advanced toward the work engaging said fingers and separating them to release the endmost rivet, and means adapted when the device is withdrawn from the work to externally

5

engage the convergent ends of said fingers for preventing their expansion.
